United States Patent Office

Des. 182,064
Patented Feb. 11, 1958

182,064

COVERED DUPLEX VEHICLE SEAT

Walter B. Dean, Narberth, and Richard M. Irwin, Philadelphia, Pa., assignors to The Budd Company, Philadelphia, Pa., a corporation of Pennsylvania

Application January 29, 1957, Serial No. 44,653

Term of patent 14 years

(Cl. D15—8)

FIG. 1

FIG. 3

Fig. 1 is a front angled perspective view of a covered duplex vehicle seat, showing our new design;

Fig. 2 is a rear perspective view of the seat; and

Fig. 3 is a side elevation.

We claim:

The ornamental design for a covered duplex vehicle seat, substantially as shown.
